CLAIM

The ornamental design for a toy, as shown and described.

DESCRIPTION

FIG. 1 is a first perspective view of a toy showing my new design;
FIG. 2 is a second perspective view thereof;
FIG. 3 is a front view thereof;
FIG. 4 is a back view thereof;

FIG. 5 is a left side view thereof;
FIG. 6 is a right side view thereof;
FIG. 7 is a top view thereof;
FIG. 8 is a bottom view thereof; and,
FIG. 9 is an enlarged view of the selected portion 9 in FIG. 1.

The dash-dash broken lines shown in the drawings depict portions of the toy that form no part of the claimed design. The dot-dash broken lines in FIG. 1 and 9 illustrate the periphery of the enlarged views of the toy and form no part of the claimed design.
